UNITED STATES PATENT OFFICE

2,152,316

ANTENNA

Roman Kopanski, Cleveland, Ohio, assignor to
The Ward Products Corporation, Cleveland,
Ohio

Application July 22, 1938, Serial No. 220,791

5 Claims. (Cl. 250—33)

This invention relates to an improved radio antenna, especially adapted for use on an automobile.

As is well known, there is now in quite general use a telescopic form of radio antenna on automobiles; and it is also quite well known that there is considerable rattle between the telescoping parts of this type of antenna, such rattle being caused by the vibration from the movement and jarring of the automobile.

It is therefore the object of my invention to devise an antenna of the type mentioned with means for preventing such objectionable rattle.

More specifically, it is my object to devise an adjustable telescoping form of antenna with means for preventing rattle regardless of the position to which it might be adjusted.

It is also the object of my invention to devise a practical and economical means for preventing rattle in a telescopic form of antenna and, by the same means, to improve the radio reception.

Other objects will appear from the following description and claims when considered together with the accompanying drawing.

Fig. 1 is an elevation of my improved antenna;
Fig. 2 is a view taken on line 2—2 of Fig. 1; and

Fig. 3 is a view taken on line 3—3 of Fig. 2.

It is to be understood that the present form of disclosure is merely for purposes of illustration and that there may be devised various modifications therein without departing from the spirit of my invention as herein set forth and claimed.

Referring to the accompanying drawing, the antenna comprises the outer metal tube 1, the inner metal tube 2 and the metal rod 3, all of which are arranged for telescopic adjustment.

The inner tube 2 is open at its inner end which is also bulged entirely thereabout, as indicated at 2^a, so as to provide uniform frictional engagement with the wall of the outer tube 1. The inner tube 2 is also provided with the apertures 4 near the inner end thereof, for a purpose to be explained.

The rod 3 has its inner end portion bent so as to provide frictional engagement at the two points 5 and 6 with the wall of the inner tube 2.

Except for the frictional engagement at the inner ends of the tube 2 and the rod 3, as just explained, these two members are otherwise spaced from each other and the inner tube 2 is otherwise spaced from the outer tube 1.

The upper end of the outer tube 1 is provided with the screw-threaded packing nut 7 and the packing or sealing washer 8, which effect a sealed

closure for this end of the outer tube 1 and also a sealed connection about the inner tube 2 which is adapted to slide therethrough.

Likewise, the upper end of the inner tube 2 is provided with the screw-threaded packing nut 9 and the packing or sealing washer 10 through which the rod 3 extends in the same manner as just explained.

As indicated in the drawing, practically the entire internal space of the antenna is filled 10 with a liquid of a certain character, as will be explained. This liquid is applied through the open lower end of the outer tube 1 after the parts are all otherwise assembled and while in inverted fully telescoped position. When the 15 lower end of the outer tube is closed by the screw plug 12, and thus the liquid is sealed within the antenna.

The antenna, as above described, is supported in the holding means 13 which may be attached 20 to the automobile, with the necessary electrical connection as usual.

The liquid 11 may be glycerine, castor oil, mineral oil, motor oil or other liquids of similar character, it being essential that the liquid be 25 capable of preventing clattering or rattling contact between the parts, as would otherwise result from vibration of the same set up by roughness of the road during motion of the automobile. Water, for instance, does not possess this 30 property and is therefore not suited for this purpose, and the same thing is true of other liquids of like character.

As will be seen, the liquid practically fills the space between the tubes 1 and 2 and the rod 3 35 when they are in telescoped position. Then when tube 2 and rod 3 are extended to various positions, the liquid will still practically fill the space between the tube 2 and the rod 3 as well as the space between the tubes 1 and 2. If, for instance, 40 the tube 2 and rod 3 should be raised together and left to occupy such position, with the rod 3 in telescoped position within the tube 2, a continuous concentric column of the liquid will still fill the space between the tube 2 and the rod 3, 45 this column of liquid following with the tube 2 and the rod 3. As well as can be judged, this is due to capillary attraction or simply adhesion and cohesion.

Without excluding other theories in an attempt 50 to explain how the liquid prevents rattle, this phenomenon is believed to be due to the pronounced surface or skin tension of the liquid. That is, the liquid possesses sufficient shock resistance or film strength not to break down under 55

the strain of vibration of the parts; and thus there is prevented the objectionable metal-to-metal clatter or rattle.

5 The packing washers 8 and 10 serve not only to seal the liquid against escape at these points, but the tube 2 and rod 3 are thereby kept free of the liquid outside of the tube 1. These washers serve also as an additional means of preventing rattle at these points.

10 The opening at the inner end of the tube 2 and the apertures 4 permit passage of the liquid so as to facilitate adjustment of the antenna.

Thus, when the antenna is in telescoped or collapsed position or when in partially or fully extended position, the tubes 1 and 2 and the tube 2 and rod 3 are always separated by the liquid so as to prevent clattering between the parts, as would otherwise be caused by vibration.

15 As is quite evident, the medium adopted by me for preventing rattle is of a non-mechanical or non-metallic nature and there is nothing to get out of order. Furthermore, it is very inexpensive and can be applied in a very simple manner.

20 25 Incidentally, the presence of the liquid in the antenna will serve also as a means of clarifying the radio reception by eliminating foreign noises and static.

25 The same invention as herein disclosed can be embodied also in other devices, as, for instance in a telescopic fishing rod.

What I claim is:

30 35 40 45 1. A radio antenna comprising a hollow metallic tubular member, a longitudinally extensible metallic member mounted within said tubular member, and a liquid of comparatively high surface tension within said tubular member and substantially and continuously filling the space between said members during all positions of the extensible member, whereby there will be prevented a rattling of the same in any adjusted position.

2. A radio antenna comprising a hollow metallic tubular member, a longitudinally extensible hollow metallic tubular member mounted within said first tubular member, a longitudinally ad-

justable metallic member mounted within said second tubular member, said members having means of continuously free communication throughout the entire space therebetween, and a liquid of comparatively high surface tension within said first tubular member and substantially filling the space between said members, whereby there will be prevented a rattling of the same.

3. A radio antenna comprising a hollow metallic tubular member, a longitudinally extensible hollow metallic tubular member mounted within said first tubular member, and having restricted contact with the inner surface thereof and being otherwise spaced therefrom, a longitudinally adjustable metallic member mounted within said second tubular member and having restricted contact with the inner surface thereof and being otherwise spaced therefrom, said members having means of continuously free communication throughout the entire space therebetween, and a liquid of comparatively high surface tension within said first tubular member and substantially filling the space between said members, whereby there will be prevented a rattling of the same.

4. In a device of the class described, the combination of longitudinally telescopic metallic members, a liquid of comparatively high surface tension substantially and continuously filling the space therebetween during all positions of the members, and means for sealing the liquid therewithin, whereby there will be prevented a rattling of the same.

5. A radio antenna comprising a hollow metallic tubular member, a second metallic member extensibly mounted within said tubular member, a body of liquid having a surface tension corresponding approximately to that of glycerine substantially and continuously filling the space therebetween during all positions of the extensible member, and means for sealing the liquid therewithin, whereby there will be prevented a rattling of the same.

ROMAN KOPANSKI.
